UNITED STATES PATENT OFFICE.

BERNARD T. LEVEQUE, OF WENHAM, MASSACHUSETTS, ASSIGNOR TO UNITED SHOE MACHINERY CORPORATION, OF PATERSON, NEW JERSEY, A CORPORATION OF NEW JERSEY.

SEWING MACHINE.

Original application filed September 26, 1918, Serial No. 255,849. Divided and this application filed December 5, 1922. Serial No. 605,002.

The invention relates to driving and starting mechanism for sewing machines and other machines having reciprocating parts corresponding to the needle bars or carriers of sewing machines which should be uniformly brought into definite position upon the completion of an operation.

The present application is a division of application Serial No. 255,849, filed September 26, 1918, and the invention will be further explained in connection with its application to the buttonhole sewing machine in said application.

The sewing mechanism of the above machine consists of upper and under needle carriers in the form of needle bars and these needle carriers should be brought to rest in retracted position free of the work at the completion of the sewing operation. To accomplish this result the needle carriers are actuated from a continuously rotating sewing shaft through connections which permit each carrier to be retained at the limit of its retracting stroke when a seam has been completed, while the shaft and unarrested members of the connections may continue to move independently of the carrier, thus avoiding the shock and wear incident to arresting the rapidly moving shaft and connections at a definite point in the cycle in order to bring the needles into proper stopped positions. The needle carriers may be disconnected from the sewing shaft and retained in their retracted positions by devices which are automatically actuated at the completion of the sewing and at the same time the sewing shaft may be disconnected from its driving power. The sewing mechanism may, therefore, be run at high speed and may uniformly be brought to stopped position at the end of the sewing without undue shock and wear regardless of its speed and regardless of variations in speed incident to operating conditions.

The features of the invention indicated above, as well as further features referred to in the claims, will be understood from an inspection of the accompanying drawings and the following detailed description of the mechanism illustrated therein.

In the drawings Fig. 1 is a sectional elevation showing the stitch forming mecha-

nism and the forward part of the actuating and stopping mechanism therefor, Fig. 2 is a similar view showing the rear part of the stopping and actuating mechanism, Fig. 3 is a front elevation of the stop mechanism for the lower needle bar, Fig. 4 is a side elevation of the same looking toward the left from Fig. 3, Fig. 5 is a plan view of the same, and Fig. 6 is a rear elevation partly in section of the driving mechanism.

The machine to which the invention has been applied comprises stitch forming mechanism including an upper needle and an under needle and looper, a sewing shaft by which the stitch forming mechanism is actuated, and a main cam shaft which is driven at high speed both before and after the sewing to control and actuate the mechanisms which operate during these periods in the buttonhole making cycle and is driven at slow speed during the sewing to relatively move the stitch forming mechanism and work clamp to sew an overseam about the edge of a buttonhole.

As shown in the drawings the upper needle 2 is carried by a vertical needle bar 4 mounted to reciprocate in and turn with a sleeve 6 which is rotated during the sewing about the eye and bar end of the buttonhole. The under needle is carried by a needle bar 10 mounted on a turret 12 which rotates in unison with the sleeve 6 and also carries a looper 14 and the under needle and looper operating mechanism.

Both the upper needle bar and the under needle and looper mechanism are connected with parts which reciprocate synchronously therewith and are actuated from a continuously rotating shaft through connections which permit the reciprocating parts to be arrested and held at the limit of their needle retracting strokes without requiring the arrest of the shaft and connections through which motion is normally transmitted to the reciprocating parts. Means is also provided for disconnecting the power from the actuating shaft and for arresting the movement of the reciprocating parts and the connected needles to stop the stitch forming mechanism in proper position for the spacing of the work when the sewing of the buttonhole has been completed.

The mechanism for actuating the under

needle and looper mechanism comprises a lever 16 which is connected with the under needle and looper operating mechanism on the turret by a link 18 so that the reciprocation of the under needle is synchronous with the reciprocation of the lever. The lever is mounted on a fixed shaft 20 and is oscillated during the sewing from a continuously running shaft 22 which is provided with a crank 24 connected by a link 26 with one arm of a bell crank lever 28, the other arm of which is provided with a lateral projection 30 overlying the lever 16. The lever 16 is normally held in engagement with the projection 30 on the lever 28 by a heavy spring 32 coiled about the hub of the lever 28 and having one end engaging a lug 34 on the lever and the other end engaging the under side of the lever 16. The levers 28 and 16 are also normally locked together by a latch 36 pivoted on the lever 16 and provided at its upper end with a shoulder adapted to overlie projection 30 on the lever 28. The latch is normally held in engagement with the projection by a spring 38. During the sewing, therefore, the levers 28 and 16 move together and transmit motion from the actuating crank on the shaft 22 to the under needle bar and looper.

When the stitch forming mechanism is to be arrested at the end of the sewing the latch 36 is disengaged from the lever 28 and the lever 16 is retained in its lower or needle retracted position by a stop dog 40 having a shoulder 42 adapted to be brought into position over the lever, and also provided with a finger 44 which is brought into the path of a roll 46 on the latch 36 during the final downward movement of the lever 16 and thus disengages the latch. The stop dog is mounted on a fixed pivot 48 and is provided with a laterally projecting tail piece 50 which overlies the forward end of a bell crank lever 52. During the sewing the bell crank lever holds the stop dog in its inactive position indicated in Figs. 4 and 5. When the stitch forming mechanism is to be arrested at the end of the sewing the bell crank lever 52 is rocked to release the stop dog which is then forced towards its active position by the spring 54 (Fig. 3). When the lever 16 is in its upper or needle advanced position during the last stitch forming cycle the bell crank lever is thus rocked to release the stop dog by a cam lever 56, operated by a cam 58 on the cam shaft 60 of the machine and having its upper end connected by a link 62 with the bell crank lever. When the stop dog is thus released it swings toward the right in Fig. 3 and rides against the side of the lever 16 during the downward or needle retracting stroke of the lever so that the latch 36 is disengaged from the lever 28 by the finger 44. When the lever passes below the shoulder 42 the dog

screws forward into active position as indicated in Fig. 3 and retains the lever 16 and the connected under needle and looper mechanism in retracted position during the continued movement of the actuating shaft 70 22 which is permitted and resisted by the yielding of the spring 32.

When the under needle and looper are arrested at the completion of the sewing the tension for the under thread is also released 75 by the engagement of the tail 50 of the stop dog 40 with a tension release lever 64 which acts on a pin 66 to separate the tension disks 68 and thus release the under thread tension.

The mechanism for stopping the upper 80 needle bar in retracted position is similar in construction and mode of operation to that for stopping the under needle in its retracted position. The upper needle bar is reciprocated through a lever 70 mounted 85 on a stationary shaft 72 and connected to an adjustable sleeve 74 on the bar by links 76 so that the lever and bar reciprocate synchronously. The lever 70 is oscillated through a bell crank lever 78, one arm of 90 which is provided with a projection 80 which is normally held in engagement with the lever by the spring 82 and latch 84. The lever 78 is oscillated to advance and retract the upper needle bar by a crank 86 on the 95 shaft 22 connected by a link 88 to the knuckle of two toggle links 90 which connect the lower end of the lever 78 to a fixed pivot 92. The latch 84 is disconnected from the lever 78 and the lever 70 with its connected needle bar are retained in retracted position at the end of the sewing by the stop dog 94 controlled by the bell crank lever 96 which is connected by a link 98 to the upper end of the cam operated lever 56 105 so that the stop dog is released during the last stitch forming cycle to retain the lever 70 and needle bar in retracted position during the continued movement of the actuating shaft and of the connections through 110 which motion is normally transmitted therefrom to the lever 70.

When the upper needle is arrested in its retracted position the tension on the upper 115 needle thread is released through a tension releasing lever 100 engaged by the tail of the stop pawl 94.

The clutch through which the sewing shaft 22 is driven is disengaged when the sewing is completed and as the stop dogs for the levers 16 and 70 are moved into active position and the resistance of the springs 32 and 82 after the levers have been arrested act to overcome the momentum of the shaft and the motion transmitting parts and also act through the cranks 86 and 24 to finally bring the shaft to rest with the levers 28 and 78 in engagement with the levers 16 and 70. The sewing shaft is thus uniformly brought to rest with the connec- 125 130

tions therefrom to the needle bars in normal relation ready for the succeeding sewing cycle.

- By the above mechanism the stitch forming mechanism is arrested or stopped by disconnecting it from the actuating shaft when the needles are in retracted position and the mechanism is at rest. The stopping of the mechanism is, therefore, effected 10 without shock or jar thereto, regardless of the speed at which the machine is run and without the necessity of stopping the actuating shaft and the entire train of mechanism through which motion is transmitted 15 at a definite point in the rotation of the shaft. The sewing mechanism may, therefore, be uniformly brought to stopping position at the end of the sewing without shock or wear when operating at high speed. 20 The mechanism for driving the cam shaft 60 which carries the cam 58 for controlling and timing the stopping of the stitch forming mechanism and also the cams for operating and controlling the various parts 25 and mechanisms of the machine comprises a worm wheel 102 secured to the cam shaft and a worm 104 engaging the worm wheel and adapted to be rotated either continuously at high speed prior to and after the sewing 30 or to be rotated intermittently from the sewing shaft 22 during the sewing. The worm is secured to a sleeve mounted to turn on the shaft 22 and provided at its end with a clutch member 106, the inner zone 35 of which is arranged to be engaged by a clutch member formed on the inner end of the high speed driving sleeve 108, and the outer zone of which is arranged to be engaged by a clutch member on the end of 40 the intermittent slow speed work feeding clutch sleeve 110. The high speed driving sleeve is adapted to slide on the shaft 22 and is provided on its outer end with a driving pulley 112 which is provided with a 45 clutch member adapted to be engaged by a clutch member 114 secured to the shaft 22. The feed clutch sleeve 110 is oscillated during the sewing from the shaft 22 through an eccentric 116 on the shaft and a series 50 of levers and links indicated at 118. During the sewing the feed clutch is engaged with the worm sleeve during its advance or feeding stroke and is disengaged from the worm sleeve during its return or idle 55 stroke by an eccentric 120 driven from the shaft 22 through the gears 122 and oscillating the clutch shifting lever 124 through the link 126.

The clutches for actuating the cam shaft 60 and the sewing shaft are thrown into and out of action through a lever 128, the upper end of which is provided with arms embracing the high speed clutch sleeve 108 and provided with pins engaging an annular groove 130 in the sleeve. The hub of the lever is

provided with a finger 132 arranged to engage a finger 134 on the lever 124 to disengage the feed clutch 110 when the lever 128 is moved to shift the clutch sleeve 108 into neutral position or into position to engage 70 its clutch member with the clutch member 106. The horizontal arm of the lever 128 is connected with a cam lever 136 by a link 138, the upper end of which slides through a block 140 pivoted to the lever 136. A 75 spring 142 normally holds a collar on the link in engagement with the under side of the block so that the levers 128 and 136 will move in unison. The lever 136 carries a roll engaged by a cam groove 144 formed in the rear face of the cam disk 58. The cam groove is so shaped that at the end of the cycle of operations performed by the machine it will hold the parts in the positions indicated in Fig. 6 with the driving clutches 80 for the cam shaft 60 and sewing shaft 22 in disengaged or neutral position.

The machine is started by a starting lever 146 connected by a rod 148 with a treadle. The starting lever is secured to the outer end of a rock shaft 150 to the inner end of which a lever 152 is secured. One end of the lever is arranged to engage the upper end of the link 138 and the other end carries a roll engaging a concentric groove 154 90 formed in the rear face of the cam disk 58 and provided with a recess 156 which registers with the roll when the parts are in starting and stopping position at the end of the cycle. 95

To start the machine the starting lever is operated to depress the link 138 and thus operate the cam shaft lever 128 to engage the high speed clutch sleeve 108 with the clutch member 106. This starts the cam shaft at 100 high speed and during the first part of the revolution of the cam shaft the starting lever is held by the operator. As the point 158 in the cam groove 144 reaches the roll on the end of the lever 136 the cam 160 at the end of the recess 156 acts on the lever 152 to release the link 138 so that during the remainder of the cycle the levers 128 and 136 move in unison. At this point the cam 144 moves the levers 128 and 136 to shift the clutch sleeve 108 toward the left in Fig. 6, disengaging it from the clutch member 106 and engaging the pulley 112 with the clutch member 114. This starts the sewing shaft 110 and also starts the intermittent feed of the cam shaft 60. The parts are so timed that as the sewing of a buttonhole seam is completed the point 162 in the cam 144 reaches the roll and the lever 136 so that the cam moves this lever and lever 128 to shift the clutch sleeve 108 to the right, disengaging the pulley 112 and clutch member 114 and re-engaging the sleeve with clutch member 106. The cam shaft is now again 115 driven at high speed for the remainder of 120 the cycle. 125

its revolution, when the cam 144 moves the levers 136 and 128 to shift the clutch sleeve 108 into neutral or stopping position. The recess 156 is now again in register with the roll on the lever 152 so that the starting lever 5 may be again operated by pressure on the treadle to start or continue the operation of the machine.

While the invention has been shown and 10 described as applied to a buttonhole sewing machine it will be understood that it is not confined in its application to such machine but may be embodied in other sewing machines or in machines in which the mechanism 15 for operating on the work includes a reciprocating part or parts corresponding to the needle carrier or carriers of the stitch forming mechanism of a sewing machine which at the completion of an operation is 20 to be brought to rest and retained at the limit of its stroke.

What is claimed is:

1. A machine having, in combination, operating mechanism including a reciprocating part, a rotating shaft, connections through which motion is normally transmitted from the shaft to the part constructed to permit independent rotation of the shaft upon arrest of the part, and mechanism 30 acting automatically to disconnect the shaft from its driving power and to retain the part in arrested position during continued movement of the shaft.

2. A machine having, in combination, operating mechanism including a reciprocating part, an actuating shaft, connections through which motion is normally transmitted from the shaft to the part constructed to permit independent rotation of the shaft 40 upon arrest of the part, and mechanism acting automatically to retain the part in arrested position during the continued movement of the shaft and for disconnecting the shaft from its driving power and bringing 45 it to rest with the connections in normal position.

3. A machine having, in combination, operating mechanism including a reciprocating part, a rotating shaft, connections 50 through which motion is normally transmitted from the shaft to the part constructed to permit independent rotation of the shaft upon arrest of the part at the end of its retracting stroke, and mechanism acting 55 automatically at the completion of an operation to disconnect the shaft from its driving power and to retain the part at the end of its stroke during the continued movement of the shaft.

60 4. A machine having, in combination, operating mechanism including a reciprocating part, an arm connected to operate synchronously with the part, a lever, a latch for normally connecting the lever and arm, an 65 actuating shaft connected to oscillate the

lever, and mechanism acting automatically to disengage the latch and retain the arm in retracted position and to disconnect the shaft from its driving power and to bring it to rest in stopping position.

70 5. A machine having, in combination, operating mechanism including a reciprocating part, an arm connected to oscillate synchronously with the part, a lever normally held in engagement with the arm by a spring, an actuating shaft connected to oscillate the lever, a normally inactive stop dog, and means acting automatically to render the dog active at the end of an operation to retain the arm at one end of its oscillation.

6. A machine having, in combination, an operating mechanism including a reciprocating part, an arm connected to operate synchronously with the part, a lever, an actuating shaft connected to oscillate the lever, a normally inactive dog for retaining the arm at one end of its oscillation, a spring connecting the lever and arm to permit continued movement of the shaft and connections upon arrest of the arm and to return them to normal relation with the arm when the shaft is disconnected from its driving power, and mechanism for disconnecting the shaft from its driving power and rendering the dog active.

7. A sewing machine having, in combination, stitch forming mechanism including a reciprocating needle carrier, a rotating shaft, connections through which motion is normally transmitted from the shaft to the carrier constructed to permit independent rotation of the shaft upon arrest of the needle carrier at the end of its needle retracting stroke, and mechanism acting automatically at the completion of the sewing to disconnect the shaft from its driving power and to retain the needle bar at the end of its stroke during the continued movement of the shaft.

100 8. A sewing machine having, in combination, stitch forming mechanism including reciprocating upper and under needles, a rotary actuating shaft, connections for normally transmitting motion from the shaft to the needles, including parts reciprocating synchronously with the needles, and means for disconnecting said parts from the shaft and retaining them at the limit of their needle retracting strokes at the end of the sewing.

105 9. A sewing machine, having, in combination, stitch forming mechanism including a reciprocating needle carrier, an actuating shaft, connections through which motion is normally transmitted from the shaft to the needle carrier constructed to permit independent rotation of the shaft upon arrest of the carrier at the end of its needle retracting stroke, and mechanism for retaining the

carrier at the end of its stroke during the continued movement of the shaft and for disconnecting the shaft from its driving power and bringing it to rest in stopping position at the end of the sewing.

10. A sewing machine having, in combination, stitch forming mechanism including upper and under needles, arms connected to reciprocate synchronously with the needles, an actuating shaft, connections for normally transmitting motion from the shaft to the arms constructed for independent movement, stop dogs for retaining the arms in needle-retracted position, and mechanism for disconnecting the shaft from its driving power and for rendering the dogs active at the completion of the sewing. 70

10. A sewing machine having, in combination, stitch forming mechanism including an actuating shaft, connections for normally transmitting motion from the shaft to the arms constructed for independent movement, stop dogs for retaining the arms in needle-retracted position, and mechanism for disconnecting the shaft from its driving power and for rendering the dogs active at the completion of the sewing. 75

11. A sewing machine having, in combination, stitch forming mechanism including a reciprocating needle carrier, an arm connected to oscillate synchronously with the needle carrier, a lever normally held in engagement with the arm by a spring, an actuating shaft connected to oscillate the lever, and a normally inactive stop dog rendered active at the end of the sewing to retain the arm at one end of its oscillation. 80

12. A sewing machine having, in combination, stitch forming mechanism including a reciprocating needle carrier, an arm connected to operate synchronously with the needle carrier, a lever, a latch for normally connecting the lever and arm, an actuating shaft connected to oscillate the lever, and mechanism acting automatically at the end of the sewing to disengage the latch and arrest the arm in needle retracted position, and to disconnect the shaft from its driving power and bring it to rest in stopping position. 85

13. A sewing machine having, in combination, stitch forming mechanism including a reciprocating needle carrier, a rotating shaft, connections through which motion is normally transmitted from the shaft to the carrier constructed to permit independent rotation of the shaft upon arrest of the needle carrier, and mechanism acting automatically at the completion of the sewing to disconnect the shaft from its driving power and to retain the needle carrier in position during the continued movement of the shaft. 90

14. A sewing machine having, in combination, stitch forming mechanism including reciprocating upper and under needles, a rotary actuating shaft, connections for normally transmitting motion from the shaft to the needles including parts reciprocating synchronously with the needles, and means for disconnecting said parts from the shaft and retaining them in position at the end of the sewing. 100

15. A sewing machine having, in combination, stitch forming mechanism including a reciprocating needle carrier, an actuating shaft, connections through which motion is normally transmitted from the shaft to the needle carrier constructed to permit independent rotation of the shaft upon arrest of the carrier, and mechanism for retaining the carrier in stopped position during the continued movement of the shaft and for disconnecting the shaft from its driving power and bringing it to rest in stopping position at the end of the sewing. 105

a reciprocating needle carrier, an actuating shaft, connections through which motion is normally transmitted from the shaft to the needle carrier constructed to permit independent rotation of the shaft upon arrest of the carrier, and mechanism for retaining the carrier in stopped position during the continued movement of the shaft and for disconnecting the shaft from its driving power and bringing it to rest in stopping position at the end of the sewing. 70

16. A sewing machine having, in combination, stitch forming mechanism including a reciprocating needle carrier, an arm connected to oscillate synchronously with the needle carrier, a lever normally held in engagement with the arm by a spring, an actuating shaft connected to oscillate the lever, and a normally inactive stop dog rendered active to stop the arm at the end of the sewing. 80

17. A sewing machine having, in combination, stitch forming mechanism including a reciprocating needle carrier, an arm connected to operate synchronously with the needle carrier, a lever, a latch for normally connecting the lever and arm, an actuating shaft connected to oscillate the lever, and mechanism acting automatically at the end of the sewing to disengage the latch and arrest the arm and to disconnect the shaft from its driving power and bring it to rest in stopping position. 90

18. A machine having, in combination, operating mechanism including a reciprocating part, an arm connected to oscillate synchronously with the part, an actuating lever, a spring normally connecting the arm and lever to move together, mechanism for oscillating the lever, and means rendered active at the end of an operation for retaining the arm at one end of its oscillation. 100

19. A machine having, in combination, operating mechanism including a reciprocating part, an arm connected to oscillate synchronously with the part, a lever normally held in engagement with the arm by a spring, an actuating shaft connected to oscillate the lever, a normally inactive stop dog, and means for rendering the dog active at the end of an operation to retain the arm at one end of its oscillation. 110

20. A machine having, in combination, an operating mechanism including a reciprocating part, an arm connected to oscillate synchronously with the part, a lever, an actuator connected to oscillate the lever, normally inactive means for retaining the arm at one end of its oscillation, a spring connecting the lever and arm to permit continued movement of the lever and its actuator upon arrest of the arm, and means for disconnecting the actuator from its driving power and rendering the retaining means active. 120

21. A sewing machine having, in combination, stitch forming mechanism including a reciprocating needle carrier, an arm connected to oscillate synchronously with the needle carrier, a lever, a spring normally connecting the arm and lever to move together, mechanism for oscillating the lever, and means rendered active at the completion of a sewing operation for retaining the arm at one end of its oscillation.

22. A sewing machine having, in combination, stitch forming mechanism including a reciprocating needle carrier, an arm connected to oscillate synchronously with the needle carrier, a lever, an actuator connected to oscillate the lever, normally inactive means for retaining the arm at one end of its oscillation, a spring connecting the lever and arm to permit continued movement of the lever and its actuator upon arrest of the arm, and means for disconnecting the actuator from its driving power and rendering the retaining means active.

23. A sewing machine having, in combination, stitch forming mechanism including a reciprocating needle carrier, a sewing shaft, a feed cam shaft, mechanism for actuating the cam shaft from the sewing shaft and independently of said shaft, connections through which the needle carrier is reciprocated from the sewing shaft constructed to permit independent rotation of the shaft upon arrest of the needle carrier, and controlling mechanism for disconnecting the sewing shaft from its driving power and retaining the needle carrier at one end of its reciprocation at the end of a sewing operation.

24. A machine having, in combination, operating mechanism including a reciprocating part, an arm connected to oscillate synchronously with the part, an actuating lever, a spring normally connecting the arm and lever to move together, a latch for normally connecting the lever and arm, mechanism for oscillating the lever, and means rendered active at the end of an operation for disconnecting the latch and retaining the arm at one end of its oscillation.

25. A machine having, in combination, an operating mechanism including a reciprocating part, an arm connected to oscillate synchronously with the part, a lever normally held in engagement with the arm by a spring, a latch normally connecting the lever and arm, an actuating shaft connected to oscillate the lever, a normally inactive stop dog, and means for disengaging the latch at the end of an operation and for rendering the dog active to retain the arm at one end of its oscillation.

26. A machine having, in combination, an operating mechanism including a reciprocating part, an arm connected to oscillate synchronously with the part, a lever, an actuator connected to oscillate the lever, normally inactive means for retaining the arm at one end of its oscillation, a spring connecting the lever and arm to permit continued movement of the lever and its actuator upon arrest of the arm, a latch for normally connecting the lever and arms and means for disconnecting the actuator from its driving power, disconnecting the latch and rendering the retaining means active.

BERNARD T. LEVEQUE.
